UNITED STATES PATENT OFFICE.

VICTOR W. PAGE, OF KEW GARDENS, NEW YORK.

LUBRICATOR FOR INTERMEDIATE GEARING.

Application filed November 22, 1921. Serial No. 517,036.

To all whom it may concern:

Be it known that I, VICTOR W. PAGE, a citizen of the United States, and a resident of the city of New York, Kew Gardens, 5 borough of Queens, in the county of Queens and State of New York, have invented a new and Improved Lubricator for Intermediate Gearing, of which the following is a full, clear, and exact description.

10 The present invention relates to new and useful improvements in intermediate driving gears for accessory shafts of motor vehicle motors, and it pertains more particularly to a means for lubricating the driving 15 gears.

It is one of the objects of the invention to provide a new and improved means for feeding a lubricant to the driving gears of the accessory shafts.

20 It is a further object of the invention to so construct this lubricant-feeding means that its action will be constant during the operation of the motor.

With the above and other objects in view, 25 reference is had to the accompanying drawings, in which the figure is a detail sectional view of the forward portion of an internal combustion motor.

Referring more particularly to the drawings, the reference character 5 designates the upper wall of the crank case of the motor and mounted in an opening 6 formed therein is a housing or the like 7. Mounted in the lower open center of the housing 7 30 is an anti-friction bearing 8, and said anti-friction bearing 8 serves as the centering means or support for a vertically extending shaft 9. Secured to the lower end of this shaft 9, is a bevel gear 10, and said bevel 40 gear 10 meshes with a bevel gear 11, which latter is carried by the motor crank shaft and is shown broken away in the drawings.

Extending vertically from the housing 7 is a tubular housing 12, and mounted in said 45 tubular housing 12 is a shaft 13, which is connected to the shaft 9 as shown. This shaft 13 extends vertically of the engine and serves as the means for driving the cam shaft thereof, which latter, however, is not 50 shown.

The reference character 14 designates the accessory shaft, and mounted on said accessory shaft is a gear 15. This accessory shaft 14 and gear 15 are mounted in a suitable 55 housing 16. The shaft 14 and the gear 15 are driven by means of a gear 17, and said

gear 17 is connected to a gear 18 by pins or other suitable means 19. Meshing with the gear 18 is a gear 20, and said gear 20 is mounted upon the crank shaft of the motor 60 in such a manner as to rotate therewith and furnish the driving power for the gear 18.

The heretofore mentioned gears 17 and 18 are provided with a bushing 21, and said gears are mounted to rotate upon a hollow bolt or pin 22 secured in the lower portion of the housing 16. This hollow bolt 22 has a passage 23 extending longitudinally thereof, and branching off from said passage 23 and extending through the side walls of the 70 hollow bolt 22 are passages 24, the bolt being cut away as indicated by the reference character 25 to provide a space between the hollow bolt 22 and the bushing 21. At a point adjacent the open end of the passage 23, the housing 7 is provided with an opening 30, and carried by the shaft 13 at a point adjacent the opening 30, is a dished member 31. This dished member 31 is carried by the 75 shaft 13 and is adapted to rotate therewith. 80

The device operates in the following manner:

The lubricant is fed in any suitable manner (not shown) to the cam shaft housing (not shown but with which the housing 12 communicates.) As the lubricant feeds through the cam shaft housing into the housing 12, the lubricant will pass downwardly of the housing 12 and downwardly of the shaft 13. As the lubricant passes 90 down the housing 12 and the shaft 13, it is caught by the dished member 31, and owing to the rotation of the shaft 13 and the dished member 31, the lubricant is thrown by centrifugal action from the dished member 31 through the opening 30 in the housing 7, and into the passage 23 of the hollow bolt 22. From the passage 23, the lubricant passes through the passages 24 to the space 95 formed by the cut-out portion 25, to lubricate the gears 17 and 18 carried by the bushing 21.

From the foregoing it is apparent that by the construction shown in the present illustration, the intermediate driving gears 105 of the accessory shaft will be constantly lubricated during the operation of the motor and that the lubricant is constantly fed to the intermediate gears by centrifugal action.

I claim:

1. A lubricating means for intermediate

gearing comprising a hollow bolt upon which the intermediate gearing is mounted, said hollow bolt having passages extending through its side walls, and centrifugal means mounted in alinement with said hollow bolt for supplying lubricant thereto, as and for the purpose set forth.

2. A mechanism of the class described comprising a housing, a shaft mounted in said housing, means for driving said shaft, a dished member carried by said shaft internally of the housing, an intermediate gearing, a hollow bolt for supporting said intermediate gearing, said hollow bolt alining with an opening in the housing and adapted to receive lubricant projected by the centrifugal action of the dished member through the hollow opening of the bolt.

3. A device of the character described comprising in combination, an accessory shaft, a cam shaft driving shaft, a crank shaft, an intermediate gearing for driving the accessory shaft from the crank shaft, a support for said intermediate gearing, and means carried by the cam shaft driving shaft for projecting lubricant to the intermediate gearing support to lubricate the intermediate gearing.

4. A device of the character described comprising in combination, an accessory shaft, a cam shaft driving shaft, a crank shaft, an intermediate gearing for driving the accessory shaft from the crank shaft, a support for said intermediate gearing, and centrifugal means carried by the cam shaft driving shaft for projecting lubricant to the support of the intermediate gearing support to lubricate the intermediate gearing.

5. A mechanism of the class described comprising in combination, an accessory shaft, a crank shaft, a cam shaft driving shaft, a housing for said cam shaft driving shaft, said housing having an opening, intermediate gearing for driving the accessory shaft, a support for the intermediate gearing, said support comprising a hollow bolt having its open end in alinement with the opening in the housing of the cam shaft driving shaft, and means for projecting lubricant through the opening of the cam shaft driving shaft housing into the hollow bolt for lubricating the intermediate gearing.

6. A mechanism of the class described comprising in combination, an accessory shaft, a crank shaft, a cam shaft driving shaft, a housing for said cam shaft driving shaft, said housing having an opening, intermediate gearing for driving the accessory shaft, a support for the intermediate gearing, said support comprising a hollow bolt having its open end in alinement with the opening in the housing of the cam shaft driving shaft, and centrifugal means carried by the cam shaft driving shaft for projecting lubricant through the opening of the cam shaft driving shaft housing into the hollow bolt to lubricate the intermediate gearing.

7. A lubricating means for gearing comprising a hollow bolt having an exposed open end and forming a support for said gearing, and centrifugal means in alinement with the exposed open end of said bolt for supplying lubricant to said hollow bolt.

VICTOR W. PAGE.
